UNITED STATES PATENT OFFICE

2,321,105

VACUUM AUTOMATIC CUTOUT

Frederick Saxe, Muskegon, Mich., assignor to
 General Motors Corporation, Detroit, Mich., a
 corporation of Delaware

Application December 8, 1931, Serial No. 579,787

16 Claims. (Cl. 123—179)

My invention relates to an engine starter control and aims to provide a novel means whereby, when an engine on an automobile stalls, and when the intake manifold vacuum ceases, the circuit for the starting motor will be closed, thereby putting the starting motor into operation and starting the engine, the circuit of the starting motor being opened, as soon as normal intake manifold vacuum is restored.

Another object of the invention is to provide a novel means whereby the mechanism hereinbefore referred to may be rendered operative or inoperative by manipulation of the ignition switch.

Another object of the invention is to so construct the device that the circuit closer for the circuit of the starting motor will remain open, when the accelerator pedal or fuel feed is operated to increase the motor fuel supply, the circuit closer being permitted to close when the operator takes his foot off the accelerator pedal, or otherwise cuts off the fuel supply.

In the accompanying drawings:

Figure 1 shows in side elevation, a device constructed in accordance with the invention, mounted on a portion of an automobile;

Figure 2 is a front elevation;

Figure 3 is a top plan;

Figure 4 is a vertical section taken through the device per se;

Figure 5 is a section on the line 5—5 of Fig. 4;

Figure 6 is a section on the line 6—6 of Fig. 4;

Figure 7 is a section on the line 7—7 of Fig. 6.

In Fig. 1, the numeral 1 designates the dash board of an automobile, the foot board appearing at 2. The steering column is shown at 3, and the accelerator pedal at 4, the pedal 4 being retracted by a compression spring 5. The accelerator pedal 4 is pivoted to a bell crank lever 6, fulcrumed intermediate its ends as shown at 7. The ignition switch is diagrammatically indicated by the numeral 8, and includes a handle 9. Movement of the handle 9 upwardly closes the circuit through the ignition switch. Although the ignition switch 8 is shown as being mounted on the steering column 3, it might be located elsewhere, without departing from the spirit of the invention.

The bell crank lever 6, see Fig. 3, is connected to operate the throttle valve 54 of the carburetor 53, said carburetor having its outlet leading to the intake manifold 50.

A box-like support 10 is secured to the forward side of the dash board 1. The support 10 carries the upper binding post 11 and the lower

post 12, located on opposite sides of the support, as Fig. 4 will show, the binding posts, of course, being properly insulated. The binding post 12, connected to a starting motor 51, see Fig. 3, carries an upstanding switch terminal 14, located within the support 10. The switch terminal 14 is adapted to cooperate with a vertically movable switch tongue 15 pivotally mounted on the binding post 11 as indicated at 49. See Fig. 4. A battery 52 connects onto the binding post 11 as indicated in Fig. 3.

A cylinder 16 is secured to the top of the support 10 and has a connection 17, leading to the intake manifold of the engine 50, the construction being such, in any event, that piston suction is transmitted to the top of the cylinder 16. A piston rod 18 reciprocates in a gland 19 on the lower end of the cylinder 16, and extends downwardly into the support 10. Pistons 20 and 21 are secured to the piston rod 18 and slide in the cylinder 16. The cylinder 16 has a vent 51.

An adjusting nut 22 is threaded on the piston rod 18, within the support 1. A compression spring 23 surrounds the piston rod 18. The upper end of the spring 23 abuts against the gland 19, and the lower end of the spring abuts against the adjusting nut 22. The piston rod 18 carries a lateral arm 24, see Fig. 7, said arm being held for adjustment on the piston rod by superposed nuts 25. The arm 24 carries a piece of insulation 26 which contacts with the lower surface of switch tongue 15.

A slide 27 is mounted for horizontal reciprocation in a guide 28 carried by the support 10. The slide 27 has a notch 29 defining a cam 30. The cam 30 cooperates with the insulation 26 on the arm 24 of the piston rod 18, to raise the piston rod 18, and, also, to raise the switch tongue 15 out of engagement with the switch terminal 14. A link 31 is pivoted to the slide 27 and to an arm 32 that is connected to the handle 9 of the ignition switch 8.

Referring to Figs. 4 and 6, it can be seen that a horizontally movable lever 33 is fulcrumed intermediate its ends at 34 on the casing 10. One end of the lever 33 extends into the casing, and the other end of the lever extends out of the casing. On the inner end of the lever 33 there is an upwardly extended, curved finger 35, adapted to engage under the switch tongue 15. The inner end of the lever 33 slides in a slotted stud 36 carried by the casing 10. A compression spring 37 surrounds the stud 36, one end of the compression spring engaging the inner end of

the lever, and the opposite end of the spring bearing against the casing 10.

The outer end of the lever 33 cooperates with the upper end of a second lever 38, located on the side of the casing 10, and fulcrumed intermediate its ends, as shown at 39, in Fig. 1, on the dash board 1, or elsewhere. One end of a link 40 is pivoted to the lower end of the lever 38, and the opposite end of the link 40 is pivoted to the lever 6. As previously mentioned the accelerator pedal 4 is also pivoted onto the lever 6 and pressure downwardly upon the pedal 4 causes movement of the upper end of the lever 38 towards the dash thus causing the curved finger 35 of the lever 33 to move to a position underneath the switch tongue 15 to prevent movement thereof to a contacting and operating position.

When the engine is running, and when there is sufficient piston suction in the connection 17 and in the upper end of the cylinder 16, the pistons 20 and 21 raise the piston rod 18, and the arm 24 on the piston rod rides under and swings up the switch arm 15, out of contact with the switch terminal 14, see Fig. 4 and the circuit of the starting motor 51, through the binding posts 11 and 12, is open. The spring 37 swings the lever 33 on its fulcrum 34 until the finger 35 of the lever 33 is underneath the switch tongue 15, as shown in Fig. 4. When the engine stops, and piston suction fails in the connection 17 and in the upper end of the cylinder 16, the piston rod 18 begins to move downwardly, but it cannot move downwardly to close the switch tongue 15 on the switch terminal 14, because the finger 35 of the lever 33 supports the switch tongue 15. When the operator takes his foot off the accelerator pedal 4, the spring 5, shown in Fig. 1, moves the parts in the direction of the arrows in Figs. 1 and 6. The upper end of the lever 38 of Fig. 1, engaging the outer end of the lever 33 of Fig. 6, moves the lever 33 to the position of Fig. 6 and withdraws the finger 35 of the lever 33 from beneath the switch tongue 15. The switch tongue 15 then is carried downwardly, by the action of the spring 23, and closes upon the terminal 14, thereby completing the circuit through the starting motor, and putting the engine into operation.

When the engine starts the intake manifold vacuum in the connection 17 and in the cylinder 16 raises the piston rod 18 to the position of Fig. 4 or thereabout. When the operator puts his foot on the accelerator pedal and pushes it in a direction opposite to that indicated by the arrow A in Fig. 1, the upper end of the lever 38 is moved away from the outer end of the lever 33, and the lever 33 can now respond to the spring 37, the finger 35 of the lever 33 being restored to a position underneath the switch tongue 15, as shown in Fig. 4.

Sometimes, for instance, on a hill, the intake manifold vacuum will drop down, and the piston rod 18 cannot move downwardly, and cause the switch tongue 15 to close the circuit of the starting motor, because the finger 35 of the lever 33 is underneath the switch tongue 15, as shown in Fig. 4. The operator can push forward on the accelerator pedal 4, and increase the fuel supply to the motor, at any time, without withdrawing the finger 35 of the lever 33 from beneath the switch tongue 15 and causing the switch mechanism 15-14 to close the circuit of the starting motor.

It is only by the backward or release movement of the accelerator pedal 4 that the finger

35 of the lever 33 is withdrawn from beneath the switch tongue 15, as is shown in Fig. 6.

When the operator disconnects the ignition switch 8 by the operation of the handle 9 downwardly, the link 31 moves the slide 27 to the left, see Figs. 1 and 5, and the cam 30 moves the piston rod 18 and the switch tongue 15 upwardly, in the way hereinbefore described. When the operator closes or connects the ignition switch 8 by raising the handle 9, the link 31 carries the slide 27 to the right, into the position of Fig. 5, so that the switch arm 15 is above the notch 29 in the slide 27, and then the operations hereinbefore described can take place.

Having thus described the invention, what is claimed is:

1. Starting apparatus for internal combustion engines comprising a current source, a starting motor adapted to receive current from said source, means for controlling the quantity of combustible mixture supplied to the engine, an ignition switch, means for operating said ignition switch, a starter switch adapted when closed to connect the starting motor with the current source, means operatively connected to said means for operating the ignition switch for causing the closing of said starter switch, and means operable in conjunction with the mixture controlling means for controlling the operation of said starter switch.

2. Starting apparatus for internal combustion engines comprising a current source, a starting motor adapted to receive current from said source, means for controlling the quantity of combustible mixture supplied to the engine, an ignition switch, means for operating said ignition switch, a starter switch adapted when closed to connect the starting motor with the current source, means mechanically connected to said means for operating the ignition switch, said means being effective to manually control the closing of the starter switch, and means operable in conjunction with the mixture controlling means for controlling the operation of said starter switch.

3. Starting apparatus for internal combustion engines comprising a current source, a starting motor adapted to receive current from said source, means for controlling the quantity of combustible mixture supplied to the engine, an ignition switch, means for operating said ignition switch, a starter switch adapted when closed to connect the starting motor with the current source, means operatively connected to said means for operating the ignition switch for causing the closing of said starter switch, and means operable in conjunction with the mixture controlling means for preventing the closing of the starter switch when the mixture controlling means occupies a predetermined position.

4. Starting apparatus for internal combustion engines comprising a current source, a starting motor adapted to receive current from said source, means for controlling the quantity of combustible mixture supplied to the engine, an ignition switch, means for operating said ignition switch, a starter switch adapted when closed to connect the starting motor with the current source, means operatively connected to said means for operating the ignition switch for causing the closing of said starter switch, and means operable in conjunction with the mixture controlling means for preventing the closing of the starter switch when the mixture controlling

means is moved to substantially fully open position.

5. Starting apparatus for internal combustion engines comprising a current source, a starting motor adapted to receive current from said source, a foot operated accelerator pedal for controlling the quantity of fuel mixture supplied to the engine, an ignition switch, means for operating said ignition switch, a starter switch for connecting the starting motor with the current source, means for causing the closing of said starter switch, said last named means being operatively connected to the means for operating the ignition switch, and means connected to the accelerator pedal for controlling the operation of said starter switch.

6. Starting apparatus for internal combustion engines comprising a current source, a starting motor adapted to receive current from said source, a foot operated accelerator pedal for controlling the quantity of fuel mixture supplied to the engine, an ignition switch, means for operating said ignition switch, a starter switch for connecting the starting motor with the current source, means for causing the closing of said starter switch, said last named means being operatively connected to the means for operating the ignition switch, and adapted to close the starter switch when the ignition switch is closed, and means connected to the accelerator pedal for preventing the closing of the ignition switch when the accelerator pedal is moved to a predetermined position.

7. Starting apparatus for internal combustion engines comprising a current source, a starting motor adapted to receive current from said source, a foot operated accelerator pedal for controlling the quantity of fuel mixture supplied to the engine, an ignition switch, means for operating said ignition switch, a starter switch for connecting the starting motor with the current source, means for causing the closing of said starter switch, said last named means being operatively connected to the means for operating the ignition switch, and adapted to close the starter switch when the ignition switch is closed, and means connected to the accelerator pedal for preventing the closing of the ignition switch when the accelerator pedal is substantially fully depressed.

8. Starting apparatus for internal combustion engines comprising a current source, a starting motor adapted to receive current from said source, a starter switch for connecting the starting motor with the current source, means for controlling the supply of fuel mixture to the engine, an ignition switch, manually operable means for operating said ignition switch, means mechanically connected to said last named means for controlling the starter switch and adapted to cause said starter switch to be closed when the ignition switch is closed and means operable by the fuel mixture controlling means to prevent the closing of the starter switch under certain conditions.

9. Starting apparatus for internal combustion engines comprising a current source, a starting motor adapted to receive current from said source, a starter switch for connecting the starting motor with the current source, means for controlling the supply of fuel mixture to the engine, an ignition switch, manually operable means for operating said ignition switch, means mechanically connected to said last named means for controlling the starter switch and adapted

5 to cause said starter switch to be closed when the ignition switch is closed and means operable by the fuel mixture controlling means, when said mixture controlling means is moved substantially to a position to supply the engine with a maximum supply of fuel mixture, to prevent closing of the starter switch.

10. Starting apparatus for internal combustion engines comprising a current source, a starting motor adapted to receive current from said source, a starter switch for connecting the starting motor with the current source, means for controlling the supply of fuel mixture to the engine, an ignition switch, manually operable means for operating said ignition switch, means mechanically connected to said last named means for controlling the starter switch and adapted to cause said starter switch to be closed when the ignition switch is closed, means normally operable by the engine when operating under its own power, to prevent closing of the starter switch and means operable by the fuel mixture controlling means under certain conditions for preventing closing of the starter switch.

11. Starting apparatus for internal combustion engines comprising a current source, a starting motor adapted to receive current from said source, a starter switch for connecting the starting motor with the current source, means for controlling the supply of fuel mixture to the engine, an ignition switch, manually operable means for operating said ignition switch, means mechanically connected to said last named means for controlling the starter switch and adapted to cause said starter switch to be closed when the ignition switch is closed, means normally operable by the engine when operating under its own power, to prevent closing of the starter switch and means operable by the fuel mixture controlling means when positioned so as to supply a large quantity of mixture to the engine for preventing the closing of the starter switch.

12. Starting apparatus for internal combustion engines comprising a current source, a starting motor adapted to receive current from said source, a starter switch for connecting the starting motor with the current source, means for controlling the supply of fuel mixture to the engine, an ignition switch, manually operable means for operating said ignition switch, means mechanically connected to said last named means for controlling the starter switch and adapted to cause said starter switch to be closed when the ignition switch is closed, means normally operative by engine suction when the engine is self operative, to prevent closing of the starter switch, and means operable by the fuel mixture controlling means, when the suction is ineffective to prevent closing of said starter switch.

13. Starting apparatus for internal combustion engines comprising a current source, a starting motor adapted to receive current from said source, means for controlling the supply of fuel mixture to the engine, an ignition switch and operating means therefor, a starter switch for connecting the starting motor with the current source and having fixed and movable contacts, a member operatively connected to the operating means for the ignition switch and normally positioned in the path of movement of said movable contact when the ignition switch is open, but movable when the ignition switch is closed to a position to permit movement of said contact to close the starter switch, and suction operated means for normally preventing the switch closing

movement of said movable contact when the engine is self operative.

14. Starting apparatus for internal combustion engines comprising a current source, a starting motor adapted to receive current from said source, means for controlling the supply of fuel mixture to the engine, an ignition switch and operating means therefor, a starter switch for connecting the starting motor with the current source and having fixed and movable contacts, a member operatively connected to the operating means for the ignition switch and normally positioned in the path of movement of said movable contact when the ignition switch is open, but movable when the ignition switch is closed to a position to permit movement of said contact to close the starter switch, and means operable by said mixture controlling means for preventing the switch closing movement of said movable contact under certain conditions.

15. Starting apparatus for internal combustion engines comprising a current source, a starting motor adapted to receive current from said source, means for controlling the supply of fuel mixture to the engine, an ignition switch and operating means therefor, a starter switch for connecting the starting motor with the current source and having fixed and movable contacts, a member operatively connected to the operating means for the ignition switch and normally positioned in the path of movement of said mov-

able contact when the ignition switch is open, but movable when the ignition switch is closed to a position to permit movement of said contact to close the starter switch, suction operated means for normally preventing the switch closing movement of said movable contact when the engine is self operative and means operable by the mixture controlling means for preventing such movement of the movable contact when the suction is ineffective.

16. Starting apparatus for internal combustion engines comprising a current source, a starting motor adapted to receive current from said source, an accelerator pedal for controlling the fuel mixture supplied to the engine, an ignition switch and operating means therefor, a starter switch for connecting the starting motor with the current source and having fixed and movable contacts, a member operatively connected to the operating means for the ignition switch and normally positioned in the path of movement of said movable contact when the ignition switch is open, but movable to a position when the ignition switch is closed to permit movement of said movable contact to close said starter switch, and a second member connected to the accelerator pedal and movable thereby into the path of movement of said movable contact when said accelerator pedal is depressed.
